UNITED STATES PATENT OFFICE.

WILLIAM J. CARROLL, OF WEST HAVEN, CONNECTICUT, ASSIGNOR TO SARGENT & COMPANY, OF NEW HAVEN, CONNECTICUT.

LOCK.

Application filed July 30, 1921. Serial No. 488,611.

This invention relates to locks and more particularly to hotel or corridor locks of the general type shown in the patents to A. A. Page, No. 1,150,617, granted August 17, 1915, 5 and William J. Carroll, No. 898,434, granted September 15, 1918. Locks of this general character are mounted upon doors which lead from corridors into separate rooms and are generally provided with two dead bolts directly operable respectively by keys inserted only at the inside and outside of the door, but so connected with each other that the protraction of either one of these bolts will cause the retraction of the other if the latter 10 is in protracted position. Either bolt may, however, be protracted and retracted independently of the other bolt when the latter is in retracted position. It is also desirable to provide such a lock with a movable ward 15 which is sometimes placed in the path of certain of the keys to prevent operation of the lock thereby.

One object of this invention is to provide a lock of this character with a removable operating mechanism which may be made 20 and assembled without the lock case and thereafter inserted within the case in operative relation to the two bolts, so that the various functions which are required in such 25 a lock may be performed.

Another object of this invention is to provide an operating mechanism for locks of this character, so that at least one of the bolts, usually the outside bolt, will normally 30 be under the control of a tumbler mechanism operable only by a suitable key and at the same time provide means operable by the other or inside key to release the outside bolt from the control of the tumbler mechanism.

40 A still further object of this invention is to provide a lock of this character with a swinging or pivoted ward which will be a part of the removable operating mechanism of the locks and will cooperate with the keys 45 thereof to effectively prevent the operation of the bolt by certain of the keys.

Still another object of the invention is to provide a removable lock operating mechanism which is capable of installation between 50 the two bolts with which locks of this character are provided, in such a position that the operating parts of the mechanism will cooperate with the two bolts which are mounted in the case.

55 Another object of this invention resides in

the provision of a novel operating means for locks of this character having an inside and an outside bolt, so connected that the protraction of one when the other is in protracted position will retract the latter. 60

To these and other ends the invention consists in the novel features and combinations of parts to be hereinafter described and claimed.

In the accompanying drawings:

Fig. 1 is a front elevational view of a lock embodying my improvements, with the cover of the lock case removed to expose the operating mechanism of the same, the view being taken from the outside of the door.

Fig. 2 is a front elevational view of my lock taken from the side opposite that shown in Fig. 1 and the cover being broken away to expose the operating mechanism from the other side.

Fig. 3 is a sectional view on line 3-3 of Fig. 1;

Fig. 4 is a sectional view on line 4-4 of Fig. 1;

Fig. 5 is a sectional view on line 5-5 of Fig. 1;

Fig. 6 is a sectional view on line 6-6 of Fig. 1;

Fig. 7 is a view similar to Fig. 1, but showing the position of the parts when the outside bolt has been protracted by the guest key;

Fig. 8 is a view similar to Fig. 7, but showing the inside bolt protracted by the guest key;

Fig. 9 is a view similar to Fig. 7, but showing the outside bolt in the position occupied by it when it is protracted by the display key; and

Fig. 10 is a view similar to Fig. 7, showing the position of the parts as the outside bolt is being protracted and the inside bolt is being retracted, both operations being performed by the movement of the emergency key;

Fig. 11 is a sectional view on line 11-11 of Fig. 10; and

Fig. 12 comprises a number of detailed views showing the operations of the various keys.

To illustrate the principles of my invention, I have shown at 10 a lock case provided with the usual face plate 11. While the lock shown is one commonly called a mortise lock, it will be obvious that the prin- 110

ciples of my invention may be applied to locks of other types. As shown, the lock is provided with the usual latch bolt 12, which is operated by a sliding yoke 13 actuated in turn by the roll back 14 which is non-rotatably mounted upon the stem 15 of the knob 16. Suitable springs 17 and 18 are arranged to maintain the latch bolt and the sliding yoke in their forward positions and the yoke is provided with a finger 19 positioned to contact with a cross-head 20 mounted upon the stem 21 of the latch bolt. The parts just described are of usual construction and no novelty resides therein except in combination with my improved operating mechanism to be described below.

The lock case is shown provided with an outside bolt 22 and an inside bolt 23. The terms "outside bolt" and "inside bolt" are used to refer respectively to bolts which are operated by keys from the outside and inside of the door. It is usual in locks of this construction to have key-holes for such keys in one side only of the door. For instance, the upper bolt 22 is operated by a key inserted from the corridor, while the lower bolt 23 is operated by a key inserted from the inside of the door, or by a person within the room with which the door communicates.

The stem 24 of the bolt 22 is of peculiar configuration, extending upwardly from the bolt head and then rearwardly along the upper portion of the lock case. It is provided upon the lower edge of the rearwardly extending portion with a recess 25 to receive a finger 26 mounted upon a key operated slide to be described in detail hereinafter. The bolt 23 is also provided with a stem 27 of peculiar configuration which extends downwardly adjacent the bolt head and then rearwardly in a generally horizontal direction toward the rear end of the lock case. If desired, a post or posts 28 may be mounted in the case to act as guides for the bolt stem. The stem is also provided with an upwardly facing recess 29 in its upper edge to receive a finger 30 formed upon a key operated slide 31.

The operating mechanism of my lock which actuates the bolts 22 and 23 is capable of manufacture and assembly as a unit without the lock case and thereafter insertable within the case. For this arrangement I provide two supporting plates 32 and 33 connected by a plurality of posts or the like 34, upon which the operating mechanism of the lock is mounted. The complete mechanism can then be assembled without the case and placed in position therein between the two bolts 22 and 23 making operative connection with the bolts by means of the fingers 26 and 30.

The slide 31, as shown more particularly in Fig. 2, is provided with the talons 35 and 36 for engagement with the key bit and

with slots 37 and 38, which movably support the slide upon the posts 34. A tumbler 39 is pivoted upon one of the posts 34, which is received in the slot 37 and is normally held in the position shown in Fig. 1 by a spring 40, that is, the longer rearwardly extending arm 41 is urged in a clockwise direction about the post 34. This arm 41 is provided with a small recess 42, as clearly shown in Fig. 2, and is also provided at its rear end with a finger 43. The recess 42 is adapted to receive a stump 44 upon the slide 31 (Fig. 8) when the slide is in its forward position corresponding to the position of protraction of the bolt and hold the bolt in this protracted position until the tumbler is moved to release the stump. The finger 43 is adapted to rest upon this stump when the slide is in its retracted position, as shown in dotted lines in Fig. 1, the rear face 45 of the tumbler preventing the movement of this slide to the left in Fig. 1 to protract the bolt until the tumbler has been moved to inoperative position. Such a movement is accomplished by the key bit, as shown in Fig. 10, the tumbler being swung upwardly or counterclockwise about its pivot 34 to release the stump 44 upon the slide. The tumbler 39 is also provided with an upwardly extending arm 46, the function of which will be described hereinafter. The stem 27 of the bolt 23 is provided with a finger 47, which is adapted to be disposed behind the head of the latch bolt when the bolt 23 is protracted so as to dog or dead lock the latch bolt against movement by the knob. Consequently, when the door is locked from the inside by the protraction of this inside bolt 23, the latch bolt is dogged by the finger 27 and the knob 16 cannot be turned, and thus a chambermaid or other person may ascertain whether or not the door is locked from the inside by merely trying the knob.

To operate the upper or outside bolt 22, I have provided a slide 50 upon which the finger 26 is formed. The shape of this slide 50 is more clearly shown in Fig. 2, where, as illustrated, the slide is provided with the talons 51 and 52 to be engaged by the key and the slots 53 and 54 slidably supporting this member upon posts 34. Pivotally mounted upon another of the posts 34 are a plurality of swinging tumblers 55, (three of these tumblers are shown in the drawings, but the number may be varied, if desired), each provided with a finger 56, normally resting upon a stump 57 provided upon a detent 58 (Fig. 9) pivoted upon one of the posts 34. The tumblers 55 are normally urged in a counterclockwise direction by a plurality of springs 59 and the detent 58 is normally urged in a counterclockwise direction by a spring 60. A post 58' is secured to the plate 32 and acts as a stop to prevent the detent 58 from being swung by the

spring 60 in a counterclockwise direction past the position shown in Fig. 9. The tumblers 55 have a plurality of recesses 61 in their forward faces, which, when actuated by the key into proper aligning positions, are adapted to receive the stump 57, and permit the detent 58 to swing in a clockwise direction in opposition to the force of the spring 60. It will, of course, be understood that these tumblers may only be so aligned by the use of the proper key or keys arranged for the particular lock under consideration.

The detent 58 is provided with a V-shaped lower edge formed by the two bevel surfaces 62 and 63, which cooperate with correspondingly shaped bevel surfaces 64 and 65 upon a member 66 pivoted at 67 upon the slide 50. The member 66 is provided with a straight lower edge which is adapted to rest upon the upper edge of a member 68 pivoted upon one of the posts 34 and supported by the arm 46 of the tumbler 39 to normally lie in a horizontal position, as shown in Fig. 9. It will be apparent that with the parts in this position, the member 66 is adapted to be moved forwardly and rearwardly with the slide 50, the pivoted member riding upon the upper face of the member 68.

The member 68 is normally supported in its horizontal position by contact of the arm 46 with a shoulder 69 formed thereupon. When the tumbler 39 is moved in a counterclockwise direction by the key bit inserted through the inside keyhole 70, as shown in Fig. 10, the arm 46 is moved beyond this shoulder 69, as clearly shown in this figure, thus allowing the pivoted member 68 to drop to a lower position. This in turn allows the pivoted member 66 to fall to a position clear of the detent 58, so that the slide 50 upon which the member 66 is pivoted may be slidably moved rearwardly without the usual clockwise movement of the detent 58. In this manner arrangements are made for releasing the slide 50 from the control of the tumblers 55 so that the bolt 22 may be retracted at certain times by the action of a key inserted in the inside keyhole 70 without the operation of the tumbler mechanism.

A pivoted member or walking beam 71 is pivoted at 72 to the plate 32, one end of which is adapted to engage the slide 50, while the other end is adapted to engage the slide 31. This walking beam is so arranged that only one of these slides may be in protracted position at one time and so that the protraction of one of the slides will retract the other if the retraction of the latter is permitted by the controlling tumbler mechanism. For instance, as shown in Fig. 8, if a key is inserted in the outer keyhole 73, which will protract the bolt 22, the

walking beam 71, which contacts with the slide 55 at its upper end, will be swung in a counterclockwise direction, and the lower end of this beam contacting with the slide 31 will urge this slide to its rearward or retracted position.

I have already described the manner in which the upper bolt is released from the control of its tumbler mechanism to be retracted by a key inserted through the inside keyhole 70 when the lower bolt 23 is moved to protracted position. In order that the opposite arrangement may be provided and that the tumbler 39 may be moved from the position shown in Fig. 8 where the bolt 23 is locked in protracted position by the stem 44 being received in the recess 42 of the tumbler, I have provided a lever 74 having a downwardly extending end 75 provided with a stirrup 76 in the form of a laterally projecting lug which is adapted to engage below the finger 43 and raise the tumbler 39 to release the stump 44. This position of the parts is shown in Fig. 10 where the bolt 23 is being retracted by means of the key inserted through the upper keyhole 73 and actuating the upper bolt to protracted position. The lever 74 is provided with an elongated slot 77 by which it is loosely mounted upon the same post 34 which pivotally carries the tumblers 55 and is urged in a clockwise direction by the spring 78. This lever is also provided with a horizontally extending arm 79, which, as clearly shown in Figs. 1 and 10, as well as in Fig. 5, lies closely adjacent the tumblers 55. It will be apparent that when the proper key is inserted in the upper or outside opening 73, the bit of the key will contact with the arm 79 and will serve to raise this lever from the position shown in Fig. 8 to that shown in Fig. 10, so that the stump 44 will be released by the tumbler.

A small ward 80 is formed upon the lower slide 31 and when this slide is moved to bolt 22 protracting position, this ward is moved forwardly, as shown in Fig. 10, so that it will prevent the insertion of any except certain keys into the upper keyhole. As shown, only the emergency key may be inserted into the upper keyhole when the slide 31 has been moved to protracting position by the key inserted through the inside or lower keyhole 70. Upon the same post 34 which carries the tumblers and the lever 74 is pivoted a swinging ward 81, the operation of which will now be described. This ward contains a large clearance opening 82 for the reception of the stump 26 and an elongated slot 83 to receive the post 34 upon which the detent 58 is pivoted. Communicating with the slot and opening are three recesses 84 which are adapted to receive a post 85 mounted upon the slide 50 when the latter is moved to bolt 22 protracting position. This ward is normally

urged in a counterclockwise direction by the spring 86.

The mechanism shown is adapted to be operated by a plurality of keys, five of which are shown in Fig. 12, as follows: the guest key 87, the master key or chambermaid's key 88, the grand master key 89, the display key 90 and the emergency key 91.

The operation of the mechanism is as follows: When the occupant leaves the room and locks the door from the outside by the insertion of the guest key 87 in the upper keyhole 73, the tumblers 55 are moved to a proper aligning position, so that they will receive the stump 57 to permit the detent 58 to be moved in a clockwise direction against the tension of the spring 60, under the impulse of the bevel face 64, which contacts with the face 63, thus allowing the pivoted member 66, together with the slide 50 to be moved forwardly to bolt protracting position. The pivoted ward 81 is moved upwardly in a clockwise direction by the key bit until the stump 85 upon the slide is received in the lowest of the three recesses 84, as clearly shown in Fig. 7. When the ward is in this position, the operation of any of the five keys is permitted and it will be moved to this position by the guest key, the maid's key, or the grand master key. When, however, the display key 90 is used to actuate the bolt 22 from the outside, the ward will be moved to such a position that the stump 85 is received in the intermediate one of the recesses 84 and the ward will in this position prevent the operation of any one of the three keys 87, 88 or 89 of lower order. This provides for the usual locking of the door from the outside by the display key, so that no one, not even the chamber-maid, can enter the room in the meantime, except with the display key or with the emergency key 90, which will always open the door from the outside without regard to which key has been used to lock the same. When the door has been locked from the outside with the emergency key, the pivoted ward 81 is not moved, but is permitted to remain in its lowest position shown in Fig. 1, wherein the stump 85 will be received in the uppermost one of the recesses 84 and the operation of any of the keys of lower order, including the display key, is prevented. Consequently, when the door has been locked by the emergency key from the outside, it can only be opened by a like key.

The position of the parts when the door has been locked from the inside by the guest key is shown in Fig. 8. It is apparent that the extension 92 upon the slide 31 prevents the entire rotation of the key and thus prevents its withdrawal from the lock case, while the bolt is in protracted position. If now with the door locked from the inside the proprietor or someone provided with an emergency key (the insertion of any other key

into the upper keyhole being prevented by the ward 80) desires to enter, he may do so by inserting the key in the upper keyhole and turning it to protract the upper bolt 22. The bit of the key will at this time engage the arm 79 of the lever 74 and raise this lever from the position shown in Fig. 8 to the position shown in Fig. 10, wherein the stirrup 76 which engages the finger 43 upon the tumbler 39 will be raised and will carry the rear end of the tumbler with it so as to release the stump 44 from the recess 42 and permit the walking beam 71 actuated by the slide 55 to retract the slide 31 and thereby retract the lower bolt 23. If the emergency key is now turned in the opposite direction, the upper bolt, which has just been thrown to protracted position when the lower bolt was retracted, will in turn be retracted without affecting the position of the lower bolt and the proprietor will be able to open the door. When the bolt 23 is moved from the position shown in Fig. 1 to protracted position shown in Fig. 8, the lever 74 will be swung about the post 34, upon which it is pivoted, by its spring 78, so that the stirrup 76 will be engaged below the finger 43.

I have just described the manner in which the tumbler 39 cooperating with the lower bolt 23 may be controlled by the emergency key inserted in the upper keyhole, so that the door, when locked upon the inside, may be unlocked from the outside. I will now describe the manner in which the door when locked from the outside and the occupant is inadvertently locked within the room may be opened by the guest key from the inside. To secure this function it is necessary to operate the tumblers 55 by a key inserted in the lower keyhole or to release the upper bolt from the control of these tumblers. I prefer to employ the latter method and for this reason have provided the pivoted supporting member 68 carrying the pivoted pawl 66. The position of the parts when the upper bolt has been locked from the outside is shown in Figs. 7 and 9, the member 68 being maintained in a substantially horizontal position by means of the shoulder 69 formed upon the same riding upon the upper end of the arm 46 of the tumbler 39. With the parts in this position, if the guest desires to unlock the door from the inside, he may insert his key within the lower keyhole and turn it in a direction to move the lower bolt to protracted position. The contact of the key bit with the arm 41 of the tumbler 39 swings the arm 46 clear of the shoulder 39 and allows the pivoted member 68 to drop down, thus allowing a similar movement to be enjoyed by the member 66. This releases the member 66 from the control of the detent 58 (which in turn is controlled by the tumblers 55) and permits the slide 50 to which the member 66 is connected to be moved rear-

wardly by the walking beam 71, the lower end of which is moved forwardly by the slide 31, thus moving the slide 50 rearwardly and retracting the upper bolt 22. The occupant 5 of the room may now turn his key in the opposite direction and retract the lower bolt without affecting the position of the upper bolt and the door will be unlocked.

What I claim is:

10 1. In a lock, a case, a pair of bolts mounted to move to retracted and protracted positions relatively to the case, and key actuated mechanism located entirely therebetween to operate the bolts.

15 2. In a lock, a case, a pair of bolts mounted to move to retracted and protracted positions relatively to the case, said bolts having stems extending rearwardly into the case, and key actuated operating mechanism for said bolts, 20 said mechanism being positioned entirely between said stems.

25 3. In a lock, a case, two bolts having diverging stems extending rearwardly into the case and mechanism located entirely between the stems for operating the bolts.

30 4. In a lock, a case, a pair of bolts movable to protracted and retracted positions, and a slide connected with each of said bolts to operate the same, both of said slides lying between said bolts.

35 5. A lock case, two reciprocable key operated bolts mounted therein, and mechanism for operating the bolts, said mechanism being operated by keys inserted between said bolts.

6. In a lock, a lock case, two bolts mounted therein, operating mechanism for said bolts, located therebetween, including tumbler mechanism and slides controlled thereby.

40 7. A lock case, a pair of spaced bolts mounted therein and operating mechanism located entirely between said bolts to effect independent operation thereof.

45 8. A lock case, a pair of spaced bolts mounted therein and operating mechanism located entirely between said bolts to effect the retraction of one bolt when the other is protracted.

9. A lock case, a pair of spaced bolts mounted therein and operating mechanism located entirely between said bolts to effect the retraction of either bolt when the other is protracted.

50 10. A lock case, a pair of spaced bolts mounted therein and operating mechanism located entirely between said bolts, including tumblers for controlling each of the bolts, a key for operating each of said bolts and means for controlling the tumblers of one bolt by the key of the other to permit the retraction of the former when the latter is protracted.

55 11. In a lock, a case, a pair of reciprocable bolts mounted therein and a removable swinging tumbler mechanism mounted in the

case for operating both of said bolts and having independent connection therewith.

12. In a lock, a case, a pair of reciprocable bolts mounted therein and a unitary operating mechanism for both said bolts, said mechanism having independent connection to said bolts. 70

13. In a lock, a case, a pair of reciprocable bolts mounted therein and a unitary swinging tumbler operating mechanism for both 75 of said bolts and independently connected to the bolts.

14. In a lock, a case, a pair of reciprocable bolts mounted therein and a unitary operating mechanism for both said bolts, said mechanism being bodily removable as a unit from the case. 80

15. In a lock, a case, a pair of bolts reciprocably mounted therein, a frame mounted in the case and carrying mechanism for operating both of said bolts. 85

16. In a lock, a case, a pair of bolts reciprocably mounted therein, a frame removably mounted in the case and carrying mechanism for operating both of said bolts. 90

17. In a lock, a case, a pair of bolts reciprocably mounted therein, a frame mounted in the case and carrying a slide to operate each of said bolts.

18. In a lock, a case, a pair of bolts reciprocably mounted therein, a frame mounted in the case between said bolts and carrying operating mechanism, including controlling tumblers for both bolts. 95

19. In a lock, a case, a pair of bolts reciprocably mounted therein, a frame removably mounted in the case between said bolts and carrying operating mechanism, including controlling tumblers for both bolts. 100

20. In a lock, a case, a pair of bolts reciprocably mounted therein, a frame mounted in the case and carrying a slide to operate each of said bolts, and tumbler mechanism to control said slides. 105

21. In a lock, a case, a pair of spaced bolts reciprocably mounted therein, and mechanism, for operating both of the bolts, insertable as a unit into the casing. 110

22. In a lock, a case, a pair of spaced bolts reciprocably mounted therein, and mechanism, for operating both of the bolts, insertable as a unit into the casing, said mechanism including means to effect the retraction of one of said bolts when the other is protracted. 115

23. In a lock, a case, a pair of spaced bolts reciprocably mounted therein, and mechanism, for operating both of the bolts, insertable as a unit into the casing, said mechanism including means to effect the retraction of either of said bolts when the other is protracted. 120

24. In a lock, a case, a pair of spaced bolts reciprocably mounted therein, and mechanism, for operating both of the bolts, 125

insertable as a unit into the casing, said mechanism having tumblers to hold said bolts in protracted position, a key for each of said bolts and means whereby the operation of one of said keys to protract one of the bolts renders the tumblers ineffective to hold the other bolt protracted.

25. In a lock, a case, a pair of spaced bolts reciprocably mounted therein, and mechanism, for operating both of the bolts, insertable as a unit into the casing, said mechanism having tumblers to hold said bolts in protracted position, a key for each of said bolts and means whereby the operation of one of said keys to protract one of the bolts renders the tumblers ineffective to hold the other bolt protracted, and means to retract said last named bolt when the first is protracted.

26. In a lock, a case, a pair of bolts reciprocably mounted therein, a reciprocable slide for operating each of said bolts, and means connecting said slides whereby the protraction of one effects the retraction of the other if the latter is in protracted position.

27. In a lock, a case, a pair of bolts reciprocably mounted therein, a reciprocable slide for operating each of said bolts, and tumbler mechanism for each of said slides to hold them in protracted position, a key for each of said slides and means whereby the operation of a key for one slide renders the tumbler mechanism ineffective to hold the other in protracted position.

28. In a lock, a case, a bolt reciprocably mounted therein, a frame mounted in the case and carrying tumblers to hold said bolt in a given position until operated by the proper key and means also carried by the frame to release said bolt from the control of the tumbler mechanism.

29. A lock having a case provided with a reciprocable bolt, a frame removably mounted in the case and operating means for the bolt mounted on the frame including a detent for holding the bolt in a given position, tumblers to control the operation of said detent and means to permit the operation of said bolt irrespective of the control of said detent by the tumbler mechanism.

30. A lock having a reciprocable bolt, an operating slide separate from the bolt and connected thereto, a detent to control the operation of the slide, and means to free said slide from the control of said detent.

31. A lock having a reciprocable bolt, an operating slide separate from the bolt and connected thereto, a tumbler controlled detent to control the operation of the slide, and means to free said slide from the control of said detent.

32. A lock having a reciprocable bolt, an operating slide separate from the bolt and connected thereto, a detent to control the

operation of the slide, a pivoted member on the slide engaging with said detent and means permitting withdrawal of the pivoted member from engagement with said detent.

33. A lock having a reciprocable bolt, an operating slide separate from the bolt and connected thereto, a detent to control the operation of the slide, a pivoted member on the slide engaging with said detent, a second pivoted member supporting the first in engaging position and means to permit the withdrawal of said second pivoted member from its supporting position.

34. A lock having a reciprocable bolt, an operating slide separate from the bolt and connected thereto, a detent to control the operation of the slide, and key operated means to free said slide from control of said detent.

35. A lock having a reciprocable bolt, an operating slide separate from the bolt and connected thereto, a detent to control the operation of the slide, a pivoted member on the slide engaging with said detent and key operated means to free said pivoted member from said engagement.

36. A lock provided with a reciprocable bolt having a stem, a slide for operating said bolt, said slide being formed separately from the stem and connected thereto, a detent for controlling said slide, tumbler mechanism to control said detent, said tumbler mechanism being operated to control the detent and permit the bolt to be moved by a key, and means operable by a second key to free said slide from control of the detent.

37. A lock having a pair of reciprocable bolts, tumbler mechanism for operating each of said bolts, a detent for controlling the position of one thereof and controlled in turn by the respective tumbler mechanism and means operated by the tumbler mechanism of the second bolt to release the first bolt irrespective of the control of its detent by the respective tumbler mechanism.

38. A lock having a case provided with a reciprocable bolt, a frame removably mounted in the case, and operating means for the bolt mounted on the frame, including a detent for holding the bolt in a given position, and means to free said bolt from control of said detent.

39. A lock provided with a pair of reciprocable bolts, a detent for holding one of the bolts in a given position, tumblers to control the detent, and means associated with the second bolt to permit the operation of the first bolt, irrespective of the control of said detent by the tumblers.

40. A lock provided with a pair of reciprocable bolts, a detent for controlling the position of one of said bolts, tumbler mechanism for controlling said detent, said tumbler mechanism being operated to release the bolt by a key, the other bolt being operable by a

second key, means operable by said second key to release the first bolt from control of said detent.

41. A lock having a pair of reciprocable bolts, tumbler mechanism for operating each of said bolts, a detent for controlling the position of one thereof, a pivoted member movable with said one bolt engaging the said detent, said tumbler mechanism being operated, and said bolt being moved by a key, the tumbler mechanism of the second bolt being operable by a second key to move the latter, and means operable by the second named key to release said pivoted member from engagement with said detent to permit movement of the said first bolt, irrespective of the position of its tumbler mechanism.

42. In a lock, a case, a pair of bolts reciprocably mounted therein, tumbler mechanism, means cooperating therewith to control one of said bolts and hold it in either protracted or retracted position, a tumbler for said second bolt and means whereby the operation of said last named tumbler moves said cooperating means and releases said first named bolt from the control of its tumbler mechanism, irrespective of the condition thereof.

43. In a lock, a pair of reciprocable bolts, a plurality of tumblers and means engaging the tumblers for controlling one of said bolts and holding it in protracted or retracted position, a tumbler for controlling the operation of the second bolt, means for moving said engaging means and freeing the first bolt from the control of its tumbler mechanism, irrespective of the position thereof, said means being controlled by the tumbler of said second named bolt.

44. In a lock, a case, a pair of reciprocable bolts mounted within the case, a detent to hold one of said bolts in either protracted or retracted position, tumbler mechanism to control said detent, a tumbler to control the movement of said second named bolt, and means under control of the tumbler for said second bolt to release said detent from control of its tumbler mechanism and permit movement of said first named bolt.

45. A lock having a pair of reciprocable bolts, a detent, means to engage said detent to control the operation of one of said bolts,

a tumbler to hold the other bolt in either protracted or retracted position, and means whereby the actuation of said tumbler will move said engaging means and free said first named bolt from the control of said detent.

46. In a lock, a case, a pair of bolts reciprocably mounted therein, tumbler mechanisms for controlling the operation of each of said bolts, said tumbler mechanisms being normally operable independently of each other, and means for effecting the operation of said tumbler mechanisms for operation by the same key when one of said bolts is in protracted position.

47. A lock provided with a pair of key actuated horizontally reciprocable bolts, a movable detent and cooperating means for holding one of the bolts in a given position, and means associated with the other bolt to move said cooperating means and free the first named bolt from control of said detent irrespective of the position of the latter when said other bolt is actuated by its key.

48. A lock provided with a pair of horizontally reciprocable bolts, a movable detent, means cooperating with said detent for holding one of the bolts in a given position, and means associated with the other bolt to move said cooperating means and thereby free the first named bolt from control of its detent.

49. A lock provided with a pair of reciprocable bolts, movable tumbler mechanism, means cooperating therewith for controlling the position of one of said bolts, said tumbler mechanism being operated to release the said bolt by a key, the other bolt being operated by a second key, and means operable by said second key to move the cooperating means and release the first bolt from control of its tumbler mechanism.

50. A lock having a pair of reciprocable bolts and tumbler mechanism for controlling each of said bolts, the tumblers of one of said bolts being operable by a key, the tumbler mechanism of the second bolt being operable by a second key, and means also operable by said second key to release the first bolt from control of its tumblers irrespective of the position and without movement thereof.

In witness whereof, I have hereunto set my hand this 15th day of July, 1921.

WILLIAM J. CARROLL.
